UNITED STATES PATENT OFFICE.

CHARLES M. TARR, OF GLOUCESTER, MASSACHUSETTS.

POINTER FOR BLACKBOARDS AND MAPS.

SPECIFICATION forming part of Letters Patent No. 283,041, dated August 14, 1883.

Application filed February 13, 1883. (No model.)

To all whom it may concern:

Be it known that I, CHARLES M. TARR, of Gloucester, in the county of Essex and State of Massachusetts, have invented certain new and useful Improvements in Pointers for Blackboards and Maps; and I do hereby declare the following to be a full, clear, and exact description of the invention, such as will enable others skilled in the art to which it pertains to make and use it, reference being had to the accompanying drawing, which form part of this specification.

My invention relates to an improvement in pointers for blackboards and maps; and it consists in the combination of a rod with a sharp-pointed rubber tip which is applied thereto, as will be more fully described hereinafter.

The object of my invention is to provide a pointer which can be moved freely over blackboards, maps, and other similar surfaces without the slightest danger of marring them.

The accompanying drawing represents my invention partly in section.

A represents an ordinary rod or pointer, such as is used in connection with blackboards, maps, and charts of all kinds, and B a soft sharp-pointed rubber tip, which is applied to its end in any suitable manner.

As here shown, the tip has a socket in its inner end, into which the tenon on the end of the rod is made to catch. I do not limit myself to any precise construction in this respect, because the tenon may be made upon the tip and made to fit in a socket in the rod, or the two may be fastened together in any other way that may be preferred.

As this tip is sharp-pointed it can be used to point out figures upon the blackboard or places upon the map, or used in connection with charts of any kind, without the slightest fear of marring or breaking its surface, as is always the case with pointers made of wood or other similar material.

Having thus described my invention, I claim—

The combination of a pointer with a sharp-pointed soft-rubber tip, which is applied thereto, substantially as shown and described.

In testimony whereof I affix my signature in presence of two witnesses.

CHARLES M. TARR.

Witnesses:

S. O. SAVILLE,

WILLIAM H. DENNEN.
